[57] CLAIM

The ornamental design for a three-way T-shaped respiratory valve with single balloon, as shown and described.

DESCRIPTION

FIG. 1 is a perspective view of a three way T-shaped respiratory valve with single balloon showing our new design;

FIG. 2 is a left side elevational view thereof, the right side elevational view being a mirror image of that shown;

FIG. 3 is a front elevational view thereof;

FIG. 4 is a top plan view thereof;

FIG. 5 is a rear elevational view thereof;

FIG. 6 is a bottom plan view thereof.
